UNITED STATES PATENT OFFICE.

JULIUS J. KOCH, OF ST. LOUIS, MISSOURI, ASSIGNOR TO FRANK WICHARD,
OF SAME PLACE.

PRESSURE-REGULATOR FOR BRICK-MACHINES.

SPECIFICATION forming part of Letters Patent No. 340,049, dated April 13, 1886.

Application filed July 27, 1885. Serial No. 172,805. (No model.)

To all whom it may concern:

Be it known that I, JULIUS J. KOCH, a citizen of the United States, residing at St. Louis, State of Missouri, have invented certain new and useful Improvements in Pressure-Regulators for Brick-Presses, &c., of which the following is a specification.

This invention specially relates to brick-machines in which the upper or lower or both plungers are operated by positive mechanical powers; and it consists of a safety attachment on either or both plungers, whereby breakage of parts is avoided, and the machine is made capable of pressing pure or adulterated clay into bricks, which otherwise cannot be accomplished.

The improvements consist of a water-cylinder, into which a piston to which the plunger is attached operates, said water-cylinder being provided with a safety-valve, serving as a safety attachment, to allow the mechanical parts to complete their movements after the clay has been compressed to its full extent, giving lost motion to the plungers, allowing the cylinder to move while the plungers are stationary.

To more fully describe the construction and operation of my improvements, and to enable others to fully understand the same, reference is had to the accompanying drawings, in which—

Figure 1 is a sectional view of my improved safety attachment, showing the upper plunger up, the lower plunger down, the charger forward, the mold filled with clay preparatory to pressing, the valve being still open after having allowed water to escape from pipe. Fig. 2 is a like view of my improved safety attachment, showing the brick pressed and finished, the valve being closed. Fig. 3 is a detail section, showing brick discharged from mold.

Figs. 4 and 5 are details of the mechanism for throwing the valve open or closing same.

Similar letters refer to similar parts throughout the several views.

A is the upper plunger, and B is the lower plunger, of a brick-press. To either or both plungers I connect a water-cylinder, C, into which the opposite end, D, of the plunger operates as a piston. This water-cylinder is an intermediate attachment between the plunger

and the mechanism for operating same. Leading from the water-cylinder is a pipe, E, into which the lower shank part, e, of the water-cylinder moves, said pipe E connecting to the water-reservoir F, which must be placed above point of the plunger.

G is a valve, similar to any ordinary safety-valve, and may be set to open at any pressure desired, and to allow water to escape to permit the lower cylinder to move up or the upper cylinder down, while the plungers and pistons are stationary.

H is an air-valve to allow the air in the cylinder to escape when first filling the cylinder with water. In case sand or other foreign substance gets mixed with the clay, which will not compress to the desired thickness to make a brick of the required dimension, the plungers, after pressing their fullest capacity, stop and are stationary before the operating mechanism has fully completed its movement, which, upon the parts still pressing, would eventually cause something to give way or break where positive moving parts are used. For this purpose I have provided the safety attachment above described, which allows the parts to move up or down after the plungers are stationary, permitting the mechanisms to complete their movements without danger of breakage. The water, after the maximum pressure is reached, causes the safety-valve to open and water to escape, the cylinder moving while the plunger is stationary, giving lost motion below and above to allow the mechanisms to complete their movements.

K is a check-valve within the safety-valve, and moves in an opposite direction to open, so as to allow water to flow into the pipe and cylinder, while the lower plunger moves up to discharge the brick from the mold, as shown in Fig. 3.

I is a slide attached to the charger I', and has lugs or pins i, which engage an arm, i', of the safety-valve, the arm being turned to the right or left, opening or closing the safety-valve, to allow water to enter the cylinder and pipe, while the plungers move away from each other and the charger moves back.

In the drawings my improvements are shown as applied to the lower plunger; but the same is applicable to the upper plunger. In such

case the air-valve and the check-valve are not necessary. Thus any brick-press operated by positive-moving mechanical means becomes a practical machine when supplied with my 5 safety attachment.

Having thus fully described the construction of my pressure-regulator, the operation is as follows: Supposing the upper plunger to be up and the lower plunger to be down, and 10 the molds full of clay, as shown in Fig. 1, the valve is now closed upon the charger, completing its return motion. The upper and lower plungers now move toward each other. As soon as the desired pressure is reached 15 the plungers stop. Although the brick is not pressed to its required thickness, and the movements of the operating mechanism are not completed, the safety-valve now opens and gives the upper or lower or both plungers lost motion. The resistance being equal to the force, 20 (pressure,) breaking strain cannot take place, provided tensile strength has been taken into consideration in construction of the machine or press. Resistance and force being now equal, 25 the gearing or positive-motion mechanism for operating the plungers can now make a complete rotation or movement, the safety-valve opening after the maximum pressure is reached, permitting water to escape, allowing 30 the water-cylinders to move independent of the plungers. When pressing is completed, the upper plunger with its cylinder moves up and the lower plunger will only have to move dead weight, plus the friction of clay in the 35 molds, no resistance being offered by the upper plunger. The check-valve within the safe-

ty-valve now opens and admits water to the cylinder equal to distance the plunger moves to discharge the brick. When upper plunger is up and brick are out of the molds, Fig. 3, 40 the charger comes forward, performing the following movements: pushing the now finished brick on the table, pushing clay forward and over the molds, and opening the valve to let water into water-cylinder. Lower plunger 45 now drops, thereby filling molds with clay, and charger moves backward, closing the valve, when the plungers are ready to move toward each other and press the clay for a new brick. 50

The piston in water-cylinder will have to be made heavy enough to overcome the friction, and at the same time displace hydrostatic pressure in water reservoir.

What I claim is—

1. In a brick-press whose plungers are operated by positive mechanical powers, the combination of a water-cylinder provided with a safety-valve, with one or both plungers, substantially as herein shown and described, and 60 for the purpose set forth.

2. In a brick-press, the combination of a water-cylinder, C, pipe E, water-reservoir F, safety-valve G, check-valve h, air valve H, with one or both plungers, substantially as 65 herein shown and described, and for the purpose set forth.

JULIUS J. KOCH.
